UNITED STATES PATENT OFFICE.

WILLIAM WIBERLEY, OF PEEKSKILL, ASSIGNOR TO ISAAC HESS, OF NEW YORK, N. Y.

DESIGN FOR FRINGE.

SPECIFICATION forming part of Design No. 15,105, dated June 24, 1884.

Application filed April 14, 1884. Term of patent 8½ years.

To all whom it may concern:

Be it known that I, WILLIAM WIBERLEY, of Peekskill, Westchester county, State of New York, have invented a new and original 5 Design for Fringes and Trimmings, of which the following is a full, clear, and exact description, reference being had to the accompanying drawing, making part of this specification.

The design relates to fringes and trimmings; 10 and it consists of a fringe or trimming formed of a heading, and of drops or pendants having straight upper parts, and a number of tufted balls at the lower end.

15 A in the drawing represents a plain or ornamental heading, from which are suspended the drops or pendants B B, which have a straight upper part, *a*, having the appearance of what is known as "rat-tailed," and a number of tufted balls or similar figures, *b*, below 20 said straight upper part, said balls being sepa-

rated by contracted portions *d*. The straight rat-tailed upper part, *a*, is of less diameter than the balls and imparts a characteristic appearance to the fringe or trimming.

Having thus described my invention, I claim 25 as new and desire to secure by Letters Patent—

The design for a fringe or trimming composed of a heading and of drops or pendants having straight rat-tailed upper parts and a number of tufted balls at the lower parts, said 30 balls being separated by contracted portions, substantially as shown and described.

In testimony that I claim the foregoing as my invention I have signed it this 11th day of April, 1884.

WILLIAM WIBERLEY.

Witnesses:

PAUL GOEPEL,
SIDNEY MANN.
